[57] CLAIM

The ornamental design for a transmission fluid filter, as shown and described.

DESCRIPTION

FIG. 1 is a top plan view of a transmission fluid filter embodying my design;

FIG. 2 is a bottom plan view of the transmission fluid filter; FIG. 3 is an end elevational view of the transmission fluid filter;

FIG. 4 is an elevational view of the end of the transmission fluid filter opposite from that shown in FIG. 3;

FIG. 5 is a side elevational view of the transmission fluid filter;

FIG. 6 is an elevational view of the side of the transmission fluid filter opposite from that shown in FIG. 5;

FIG. 7 is a perspective view of the top of the transmission fluid filter;

FIG. 8 is a perspective view of the bottom of the transmission fluid filter; and,

FIG. 9 is a perspective view of the bottom of a second embodiment of my design.
